CLAIM

The ornamental design for a wireless emitter, as shown and described.

DESCRIPTION

FIG. 1 is a front/right side perspective view of the wireless emitter design.

FIG. 2 is a front view of the wireless emitter design.

FIG. 3 is a back view of the wireless emitter design.

FIG. 4 is a left side view of the wireless emitter design.

FIG. 5 is a right side view of the wireless emitter design.

FIG. 6 is a top view of the wireless emitter design; and,

FIG. 7 is a bottom view of the wireless emitter design. The broken lines shown in FIGS. 1-7 represent portions of the wireless emitter that form no part of the claim.

1 Claim, 5 Drawing Sheets
